UNITED STATES PATENT OFFICE.

CHARLES A. FORD, OF EAST ORANGE, NEW JERSEY.

PERPETUAL CALENDAR.

1,364,101.

Specification of Letters Patent.

Patented Jan. 4, 1921.

Application filed October 23, 1920. Serial No. 418,964.

To all whom it may concern:

Be it known that I, CHARLES A. FORD, a citizen of the United States, and a resident of East Orange, county of Essex, and State 5 of New Jersey, have invented certain new and useful Improvements in Perpetual Calendars, of which the following is a specification.

This invention relates to an improved calendar of the kind known as perpetual calendars, which is easily operated on account of its simplicity and has but few movable parts, the calendar being adapted to be used from year to year, the designation of the 15 month and also the columnar arrangement of dates in each month being movable so that the selected dates can be displayed through an opening in a front sheet.

The invention is further designed to provide a calendar of this kind in which a cancellation disk is employed which can be swung to cover the 30th and 31st of any month in which such cancellation is necessary.

25 The invention further consists of an index pointer which can be shifted to specify any particular date of the month as a reminder or to indicate the current date, such pointer being arranged so that it can indicate the 30 whole monthly designation of days without interfering with the operation of the other parts of the calendar.

The invention is illustrated in the accompanying drawings, in which Figure 1 is a 35 front view of my improved form of calendar, this form indicating how it can be used on a desk fixture. Fig. 2 is a face view of the disk used to indicate the month. Fig. 3 is a face view of the cancellation disk. Fig. 40 4 is a face view of the movable sheet carrying the monthly designation of dates and the cancellation disk imposed thereon, and Fig. 5 is a top view of the cancellation disk, the movable sheet and the monthly disk.

45 The calendar comprises a front sheet 10 which can be of any desired size and form, but it is shown as part of a desk fixture, being attached to the rear of the ink stand 11. The front sheet has an opening 12 therein, 50 which opening is preferably arched and through which is displayed the dates which are printed on a movable sheet 13, the movable sheet being arranged to swing on the back of the front sheet, the pivot being of 55 any usual construction, but in the form shown the back of the casing of the clock

14 acts as a pivotal support on which the movable sheet swings.

The columnar disposition of dates is so arranged that two monthly arrangements 60 are provided, one in which the first of the month would fall on Saturday, and the other in which the first of the month would fall on Sunday. The column shown at 15, which is that column that contains the beginning of the month, that is, it contains the numbers 1, 8 and 15, 22 and 29, is common to both monthly designations. At the edge of the opening 12, as at 16, are arranged the designations of the days of the week, so 70 that the movable disk 13 can be swung to indicate the first of a month as coming on any day of the week.

It will be evident from an inspection of Fig. 4 that the columnar disposition to the 75 left of and including the column 15 requires six rows of figures, and that designation extending to the right of and including the column 15 requires five.

A cancellation disk 17 is arranged so as 80 to swing on the same pivot as the movable sheet 13, the cancellation disk 17 being cut away, as at 18, one edge of which forms a cancellation portion 19 for the lowest column of figures 20 in the monthly designation to the left, this portion 19 being off-set, and a second off-set portion 21 can be used 85 to cover designated dates on the fifth row of figures in a columnar arrangement, this cancellation disk being used to cover 30 and 90 31 shown at 20 in Fig. 4, the part 21 being swung, when necessary, to cover dates on the fifth row of figures, for instance, as would be necessary to cover 29, 30 and 31 shown at 22 in Fig. 4.

95 A finger-piece 23 is supplied to the cancellation disk 17 so that it can be easily manipulated, and the ends 24 of the inner portion of the opening 12 co-operate with the finger-piece 23 to limit the movement of 100 the cancellation disk. A suitable finger-piece 25 is placed on the front of the movable sheet so that the sheet can be swung.

A disk 26 is pivoted at a suitable place, usually directly in rear of the upper part 105 of the movable sheet 13, as, for instance, on the strip 27 shown in dotted outline in Fig. 1, and is adapted to display the designation of the month through the opening 28 in the front sheet 10.

110 It is preferred that these monthly designations have in small numerals the number

of days in the month, and in the form shown in Fig. 1, if the first of May comes on Saturday and there are 31 days, the cancellation disk is not used for cancellation, 5 but when June arrives it will be evident that the column indicating the first of the month is moved to the left to Tuesday, in which case the cancellation disk would be swung to the left to cover up the 31 that 10 appears at 29 in Fig. 4. It will also be evident that if February, other than a leap year, is being designated, if the first of the month comes on Tuesday, for instance, the cancellation disk would be swung to cover 15 up also the 30 and the 29 shown at 22 in Fig. 4, the 30 and 31 illustrated at 20 in Fig. 4 being, of course, in the meantime concealed by the front sheet 10.

All that it is necessary to do, therefore, 20 to indicate any monthly calendar is to move the number one of that day on which the month begins, then moving the cancellation disk, if necessary, to cover excess dates that appear for that month.

25 As a reminder, or to indicate a particular day, I provide an arm 30 which is pivoted, as at 31, to the front sheet, the arm being looped so as to permit the passage under it of the finger-piece 23, and a pointer 32 is 30 pivoted to the end of the arm 30 so that

these two pivotal motions permit the swinging of the end of the pointer to any date in the columns to which it is desired to have it point.

Of course it will be understood that slight 35 changes can be made in the form of the calendar, and it can be suitably ornamented and can be arranged as a pocket or portable calendar instead of being affixed, as illustrated, to a desk fixture. 40

I claim:

A calendar comprising a front sheet with a display opening, a movable sheet adapted to swing behind the opening and having a columnar disposition of dates thereon to 45 indicate a month beginning on Saturday and a month beginning on Sunday, the column in which the first day of the month is arranged being common to both monthly arrangements, the edge of the opening having daily designations with which the columns can be made to register, and a cancellation disk swinging between the front sheet and the movable sheet for covering selected dates on the movable sheet. 50

In testimony that I claim the foregoing, I have hereto set my hand, this 22nd day of October, 1920.

CHARLES A. FORD.
